PICNIC JUG

Jack Bloch, Fort Worth, Tex., assignor to Loma Industries, Fort Worth, Tex., a corporation of Texas

Filed Sept. 21, 1960, Ser. No. 62,229

Term of patent 14 years

(Cl. D58—17)

FIG. 1.

Fig. 2.

The jug is cylindrical throughout its cross-section and the top of the cap portion is flat and plain.

The rear and side not shown are the same as the front and side, respectively, shown, except that the spout and corresponding cap portion are omitted.

I claim:

The ornamental design for a picnic jug, as shown and described.
